Primary Examiner — Justin M Jonaitis*Assistant Examiner* — Grace Doyle(74) *Attorney, Agent, or Firm* — Hawaii Patent Services;
Nathaniel K. Fedde; Kenton N. Fedde(57) **CLAIM**

The ornamental design for a vase, as shown and described.

DESCRIPTION

FIG. 1 is a front, top perspective view of a vase, showing my new design;

FIG. 2 is a rear, bottom perspective view thereof;

FIG. 3 is a front elevational view thereof, the rear elevational view being a mirror image of FIG. 3;

FIG. 4 is a left side view thereof;

FIG. 5 is a right side view thereof;

FIG. 6 is a top plan view thereof;

FIG. 7 is a bottom plan view thereof;

FIG. 8 is a sectional view of 8-8 along the line in FIG. 3;

FIG. 9 is a sectional view of 9-9 along the line in FIG. 3; and, FIG. 10 is a sectional view of 10-10 along the line in FIG. 4.

The oblique line shading indicates a transparent surface.

1 Claim, 10 Drawing Sheets
